[57] CLAIM

The ornamental design for a motorcycle fork end cover, as shown and described.

DESCRIPTION

FIG. 1 is an elevational view of a motorcycle fork end cover showing my new design mounted on the end of an axle fork shown in phantom lines;

FIG. 2 is a side elevational view thereof;

FIG. 3 is a side elevational view rotated 90 degrees from the view in FIG. 2;

FIG. 4 is a side elevational view rotated 90 degrees from the view in FIG. 3;

FIG. 5 is a bottom view thereof; and,

FIG. 6 is a top plan view thereof.

The broken lines in the figures are for illustrative purposes only and are not part of the claimed design.
